UNITED STATES PATENT OFFICE.

ABRAHAM COON, OF GLENWOOD, IDAHO, ASSIGNOR OF ONE-HALF TO J. L. GROSS, OF KOOSKIA, IDAHO.

ROTARY ENGINE.

No. 862,716.

Specification of Letters Patent.

Patented Aug. 6, 1907.

Application filed February 26, 1907. Serial No. 359,335.

To all whom it may concern:

Be it known that I, ABRAHAM COON, a citizen of the United States, residing at Glenwood, in the county of Idaho and State of Idaho, have invented certain new and useful Improvements in Rotary Engines; and I do hereby declare the following to be a full, clear, and exact description of the invention, such as will enable others skilled in the art to which it appertains to make and use the same.

10 This invention relates to rotary engines and especially to that class of rotary engines employing an eccentric piston.

An object of the invention is to provide in a rotary engine a rotating cylinder casing inclosing an eccentric piston of improved form with improved abutments 15 engaging said piston.

A further object of the invention is to provide in a rotary engine a rotating cylinder casing inclosing an eccentric piston, and improved abutments sliding in 20 the piston casing and engaging the piston.

A further object of the invention is to provide in a rotary engine inlet and exhaust ports, and improved means for changing the relation of such ports at will.

A further object of the invention is to provide in a 25 rotary engine a piston casing inclosing an eccentric piston having improved form of pockets formed in the sides thereof for the admission and exhausting of steam to and from the casing.

With these and other objects in view, the invention 30 comprises certain novel constructions, combinations and arrangements of parts, as will be hereinafter fully described and claimed.

In the drawings:—Figure 1 is a horizontal, sectional view of the improved rotary engine taken on line 1—1 35 of Fig. 2, with the stationary shaft and steam chest taken on line 3—3 of Figs. 3 and 4. Fig. 2 is a view of the cylinder casing with the head removed showing the relative positions of the piston and abutments and taken on line 2—2 of Fig. 1. Fig. 3 is a view of the 40 steam chest in vertical section exhibiting the tubular shaft in end elevation as taken on line 3 of Figs. 1 and 5. Fig. 4 is a view in elevation of the rotary reversing valve. Fig. 5 is a sectional detail view of the tubular shaft, cylinder chest, inlet and exhaust ports taken co- 45 incident with lines 5—5 of Figs. 3 and 4. Fig. 6 is a view in side elevation of the eccentric piston as seen on arrow 6 of Fig. 7. Fig. 7 is a view in section of the piston taken on a line perpendicular to its axis as the line 7—7 of Fig. 6. Fig. 8 is a perspective view of one of the 50 sliding abutment members.

Like characters of reference designate corresponding parts throughout the several views.

The rotary engine forming the subject-matter of this application is mounted upon any convenient or ap-

proved form of base shown conventionally at 10 and 55 comprises a cylinder casing 11, and a piston 12. The cylinder casing is provided with a head 13 and is journaled to rotate upon a shaft 14 at one end rigid therewith and upon an adjustable bearing 15, engaging the head 13 and serving also as a stuffing box. The adjustable 60 bearing 15 is mounted upon screw threads as shown particularly in Fig. 1 and formed tapered externally with its inner end abutting stuffing material shown at 16.

The cylinder casing 11 comprises an outer ring 17 upon which the head 13 is rigidly secured in any approved manner as by the employment of bolts 18 engaging within holes 19. Within the ring 17 is defined a circular chamber 20 concentric with the ring 17 and with the shaft 14 and bearing 15.

Within the circular chamber 20 is mounted the piston 12 carried upon the end of a shaft 21 and eccentric both to such shaft 21 and the chamber 20 so that one peripheral edge of the piston 12 is substantially in contact with the peripheral wall of the chamber 20 and with the opposite parallel surface of the said piston in 70 contact respectively with the cylinder head 13 and inner surface of the cylinder. The shaft 21 is provided with longitudinally extending parallel ports 22 and 23 continued by downwardly extending branches 24 and 25 terminating in pockets 26 and 27 formed in the peripheral face of the cylinder 12 and upon opposite sides 80 of and below the shaft 21.

Within the ring 17 of the cylinder casing are a plurality of slots 28 formed as continuations of diametrically disposed furrows formed in the surface and crossing at the center of the cylinder, and within which reciprocate abutment members 29. Opposite abutment members are joined by means of bars 30, halved adjacent their middles as at 31 to permit the said bars to cross and sliding diametrically in the said furrows. In 90 Fig. 1 one of the bars 31 is shown in elevation while the corresponding bar is shown in section as taken on line z—z of Fig. 8 and with the surface of the piston in frictional engagement with the bars 31 and with the inner surface of the cylinder. The abutment members 29 95 are provided with sockets 32 within which slidably operates the shank 33 of the abutments 34. It will be noted that the abutments 34 are formed with tapered sides, and with the ring 17 adjacent the socket 28 is formed with tapered sides as at 35 to permit the abutment to be seated entirely within the ring and the face of the abutments to correspond substantially with the peripheral wall of the chamber 20 as shown particularly in Fig. 2.

The shaft 21 carried rigidly by the piston 12 and remaining stationary therewith extends outwardly beyond the supporting member of the base 10 and carries at its outer end a steam chest 36 provided with a

head 37 and receiving steam or other fluid under tension through a pipe 38. The shaft 21 terminates within the steam chest 36, and a valve member 39 is mounted within the chest and abutting the extremity of the 5 shaft 21. The valve member 39 is provided with a port 40 positioned to register with either of the ports 22 or 23 and to permit the passage therethrough of the steam or other fluid from the steam chest 36 to either of said ports 22 or 23. The valve member 39 is also provided with a segmental groove 41 formed substantially similar to a horse-shoe and disposed radially from the center of such valve member to register with either of the openings 21 and 22 which is not already registering with the opening 40. The steam chest 36 is also provided with an exhaust port 42 positioned to register with the groove 41 and permitting passage of fluid under tension from one of the ports 22 or 23 through the groove 41 and through the exhaust port 42. The valve member 39 is mounted to rotate within the steam chamber 20 36 and is provided with a stem 43 extending outwardly through the head 37 and carrying upon its external end a lever or hand wheel shown conventionally at 44 and whereby the valve member 39 within the steam chest 36 may be controlled. It will be understood that when the port 40 is registering with the port 22 the port 23 is in register with the groove 41 which also communicates with the port 42 so that the port 23 in that case is the exhaust port and the cylinder casing 11 will rotate in the direction indicated by 30 the full line arrow in Fig. 2. If, however, the valve member 39 is rotated so that the port 40 registers with the port 23 then the port 23 becomes the inlet port and the port 22 the outlet port by way of the groove 41 and exhaust port 42 so that the cylinder casing is rotated 35 in the direction indicated by the dotted arrow in Fig. 2. To stop the flow of fluid into the cylinder casing the valve may be rotated so that both ports 22 and 23 are covered by the groove 41, whereupon fluid is admitted to neither of said ports and the device will not 40 be operated. It will further be understood that when fluid under tension is admitted to either of the ports such fluid will expand against the abutment and cause the cylinder casing to rotate, the pocket of the piston being so formed that the abutments bear against the 45 sides of the pocket and ride over the pocket but do not prevent the admission of fluid from the pockets to the casing 11. As soon as the casing 11 is rotated to such an extent that the opposite pocket is uncovered then the contained fluid is exhausted through that 50 pocket and its communicating ports as above described.

What I claim is:—

1. In a rotary engine, a cylinder having a concentric chamber and with furrows formed diametrically of the chamber and at right angles to each other, and with ex-

tensions projected into the wall of the chamber, abutment carriers extending transversely across the chamber and seated within the furrows, and abutments carried by the abutment carriers, a piston eccentrically mounted within the chamber and with one side in engagement with the peripheral wall of the chamber, and its periphery engaged by the abutments. 55

2. In a rotary engine, a cylinder provided with a concentric chamber, and with furrows extending at right angles diametrically of the chamber and into the peripheral wall of the chamber forming pockets therein, abutment carriers mounted within the pockets and provided with means extending diametrically across the chamber within the furrows and crossing each other centrally of the chamber, abutments carried yieldingly by the abutment carriers, a piston mounted eccentrically within the chamber and with the periphery in engagement with the abutments, and one side in engagement with the peripheral wall of the chamber. 60

3. In a rotary engine, a cylinder provided with a concentric chamber having pockets formed in its walls and tapered at the entrance to the chamber, abutment carriers slidably seated within the pockets, abutments having tapered sides carried by the abutment carriers and proportioned to be seated within the tapered extremities of the pockets, and a piston eccentrically mounted within the chamber, and in engagement with the abutments and with one side in engagement with the peripheral wall of the chamber. 70

4. In a rotary engine, a cylinder provided with a concentric chamber and with furrows extending at right angles across the chamber and terminating in pockets formed diametrically opposite within the walls of the chamber and tapered at their entrance to the chamber, abutment carriers slidably mounted within the pockets and connected by bars extending slidably within the furrows and crossing each other centrally of the chamber, abutments carried by the carriers and having tapered sides proportioned to be seated within the tapered extremities of the pockets, and a piston eccentrically mounted within the chamber and in engagement with the abutments and with one side in engagement with the peripheral wall of the chamber. 85

5. In a rotary engine, a cylinder provided with a concentric chamber having furrows formed at right angles diametrically across and terminating in pockets formed in the peripheral wall of the chamber, the said pockets having tapered extremities opening into the chamber, abutment carriers slidably mounted within the pockets and provided with slots, the said abutment carriers being connected with diametrically opposite carriers by bars extending diametrically across the chamber within the furrows, abutments slidably mounted within the slots of the abutment carriers, and having tapered sides proportioned to fit the tapered extremities of the pockets, resilient members mounted within the slots and bearing against the abutments, and a piston eccentrically mounted within the chamber and with its periphery in engagement with the abutments and one side in engagement with the peripheral wall of the chamber. 100

In testimony whereof I affix my signature in presence of 115 two witnesses.
